UNITED STATES PATENT OFFICE

EMMA M. THOMAS, OF WALTHAM, MASSACHUSETTS, ASSIGNOR TO WARREN TELECHRON COMPANY, A CORPORATION OF MAINE

DESIGN FOR A CLOCK CASE

Application filed October 30, 1931. Serial No. 41,566. Term of patent 14 years.

To all whom it may concern:

Be it known that I, EMMA M. THOMAS, a citizen of the United States, residing at Waltham, county of Middlesex, State of Massachusetts, have invented a new, original, and ornamental Design for a Clock Case, of which the following is a specification, reference being had to the accompanying drawings, forming part thereof.

Fig. 1 of the drawings is a front view of a clock case, and Fig. 2 a side view thereof, showing my new design.

I claim:

The ornamental design for a clock case as shown.

EMMA M. THOMAS.
